UNITED STATES PATENT OFFICE.

HARRY EHLIG, OF PEARL RIVER, NEW YORK, ASSIGNOR TO GEORGE R. SWART & COMPANY, INC., OF NEW YORK, N. Y., A CORPORATION OF NEW YORK.

FOLDING AND SLITTING MACHINE.

Application filed December 22, 1923. Serial No. 682,351.

To all whom it may concern:

Be it known that I, HARRY EHLIG, a citizen of the United States, and a resident of Pearl River, in the county of Rockland and State of New York, have invented certain new and useful Improvements in Folding and Slitting Machines, of which the following is a specification, reference being made to the accompanying drawings, forming a part thereof.

My invention relates to machines used for folding and slitting printed sheets or signatures as they are delivered from a printing-press or other like machine, and the objects of my invention are, among other things, to provide a machine of this type with means by which the rotary cutting bars used for longitudinally slitting the sheets as they are folded may be readily inspected and the knives as well as the bars may be removed from the machine, while the mechanism for folding and side-registering such sheets may be easily swung from operative position to afford sufficient access to the cutting bars and their knives whereby the operator may detach either or both from the machine without shifting or disturbing any part of their actuating devices or the mechanism for folding and side-registering the sheets.

Furthermore my improved machine also enables the cutting bars, folding and side-registering devices with their actuating mechanism to be readily reassembled in operative position without changing or disturbing their mutual relations with one another. A further object is to provide simple and highly efficient mechanisms for handling the successive sheets as they are folded and slit by my improved machine in which there are a minimum of operative parts so that dependability, accuracy of register, mechanical balance and high speed may be attained. These and other objects will be hereinafter fully set forth and particularly pointed out in the appended claims.

The accompanying drawings illustrate a preferred embodiment of my invention in which—

Fig. 1 is a side elevation with the various parts of my improved machine in an operating position;

Fig. 2 is a sectional side elevation of one end of the machine on an enlarged scale, the view being taken on the line 2—2 of

Fig. 3 looking in the direction of the arrows. Fig. 2 shows particularly the folder carriage partially retracted to expose the cutting bars;

Fig. 3 is a plan view of one side of the machine with certain parts broken away and parts shown in section; and

Fig. 4 is a detail sectional view on an enlarged scale taken on the line 4—4 of Fig. 1 looking in the direction of the arrow.

Similar numerals refer to similar parts throughout the several figures.

Referring to the drawings, the side-frames 5 and 6 support the various parts embodied in my machine; as shown in Fig. 1, the delivery tapes 7 travel around the rolls 8 and 9 journaled in the brackets 10 and 11 respectively (only one set being shown) mounted on the side-frames 5 and 6, on which tapes 7 the successive sheets or signatures are carried over the two cooperating folding rollers 12 and 13 mounted on shafts 14 and 15 which are journaled in suitable bearings 16 and 17 on the top of the side-frames 5 and 6. The transverse folding blade 18 to coact with the rollers 12 and 13 is mounted on the end of the rock-arm 19 secured to the rock-shaft 20 journaled in the brackets 21 on the side-frames 5 and 6, only one of such brackets 21 being illustrated in Fig. 1. Secured to the shafts 14 and 15 are the coacting gears 22 and 23 respectively to rotate the rollers 12 and 13, the shaft 14 being driven by the pinion 24 secured thereto, which pinion 24 is driven in turn by the gear-wheel 25 mounted on the transverse cam-shaft 26 journaled in the side-frames 5 and 6. The main power-shaft 27 drives the gear-wheel 25 through a pair of bevel gears 28 and 29 journaled in the bracket 30 fastened to the side-frame 5. The rock-shaft 20 is oscillated in suitable timed relation with the folding rollers 12 and 13 by the cam 31 mounted on the shaft 26 which cam engages the cam-roller 32 pinned to the end of the arm 33 fastened to the rock-shaft 20.

From the under side of the folding rollers 12 and 13 the folded sheets or signatures are carried by the forwarding tapes 34 passing around the roller 12 and then forwardly around the roller 35; the tapes 34 then travel rearwardly over idler roller 36 and tension roller 37 carried by the outer end of the arm 38 pinned to the side-frame 5.

Slidably mounted on the side-frames 5 and 6 at the forward end of the machine is the carriage 39 which supports the second folding mechanism and also the sheet-positioning or side-registering mechanisms which are adapted to be shifted forwardly so as to expose the coacting slitting mechanism which comprises suitable rotary cutting bars carrying circular knives to slit longitudinally the folded sheets or signatures. In the embodiment shown the carriage 39 is slidably held to the side-frames 5 and 6 by the screw-bolts 40 passing through elongated slots 41 into the side-frames, only one set being shown in the figures. The carriage 39 is operated on the side-frames 5 and 6 by means of the rack 42 secured to the under side of the carriage, which rack engages the gear 43 keyed to the transverse shaft 44 journalled in the side-frames 5 and 6. The outer ends of the shaft 44 carry the handles 45 by which the operator moves the carriage 39 forwardly or backwardly at will.

Journalled in the forward end of the carriage 39 is the rock-shaft 46 to which is fastened the arm 47 by the set-screw 48 (Fig. 3); the arm 47 carries on its outer end the folder blade 49 which is adapted to be reciprocated in cooperative relation between the folding rollers 50 and 51 mounted on the shafts 52 and 53 respectively. The shaft 52 is suitably journalled in the carriage 39, while the shaft 53 is rotatably mounted in the journal boxes 54 slidably and yieldingly mounted in the brackets 55 secured to the top side of the carriage 39 by means of the coil springs 56 which yieldingly hold the roller 51 in operative engagement with the roller 50. Rearwardly of the roller 50 is fastened the cross-bar 57 which carries the curved guide-plates 58 extending forwardly over the top peripheral surface of the roller 50. Across the forward end of the carriage 39 is the cross-bar 59 to which is adjustably secured the lower guide-rods 60 having their outer ends 61 flattened and curved over the top surface of the roller 51. Also adjustably fastened to the cross-bar 59 are the upper guide-rods 62 suitably spaced horizontally from the rods 60 to allow the sheets or signatures to slide therebetween before folding, with the leading edges of the sheets to contact with, and register against, the cross-plate 63 adjustably secured by the set-screw 64 to the rearwardly projecting rod 65 mounted on the bracket 66 which is adjustably fastened to the cross-bar 59 by screw-bolts 67 as shown in Figs. 2 and 3.

Any suitable side-registering mechanism to coact with the folding devices may be mounted on the carriage 39. In the embodiment shown the cross-bar 68 is slidably mounted on the carriage 39 and the bar 68 carries the side-guide plate 69 which may be transversely shifted on the bar 68 and se-

cured in any predetermined position by the set-screw 70. At one end of the bar 68 is fastened the depending bracket 71 through an opening in which passes the forwardly extended rod 72 mounted in the rock-arm 73 which is fastened to the forward end of the shaft 74 journalled in the brackets 75 and 76 (Fig. 1) carried by the side-frame 6. The rear end of the shaft 74 carries the right-angled arm 77 on the end of which is pinned the cam-roller 78 which engages the side-cam 79 mounted on the end of the cam-shaft 26 as shown in Fig. 3. The roller 78 is maintained in operative engagement with the cam 79 by the compression-spring 80 coiled about the rod 81 sliding in the frame-bracket 82 between the bracket 82 and the collar 83; the upper end of the rod 81 is pinned to the rock-arm 84 secured to the shaft 74 as shown in Figs. 1 and 3. The tension of the spring 80 normally forces the rod 81 upwardly to hold the cam-roller 78 against the cam 79. The length of the rod 72 is such that the bracket 71 is never out of engagement even when the carriage 39 is racked forwardly as shown in Fig. 2. The reciprocation of the bar 68 with the side-guide 69 is timed with the reciprocating folder blade 49 by proper setting of the cam 80 on the shaft 26, as will be readily understood by those skilled in the art.

The folder-blade 49 is raised and lowered in timed relation with the side-guide 69 by any suitable mechanism: In the present embodiment the rock-shaft 46 carries the depending arm 85 to which is pinned the rod 86, the outer end of which is formed with the slot 87 enclosing the cam-shaft 26 to hold the rod 86 in position; the tip of the rod 86 carries the cam-roller 88 which engages the cam 89 mounted on the cam-shaft 26. The roller 88 is held in engagement with the cam 89 by the compression spring 90 coiled about the rod 91 pinned at 92 to the side-frame 5 with the free end slidably held in the block 93 secured to the arm 85. The spring 90 is held under tension between the block 93 and rod collar 94 as shown in Fig. 1.

Rotatably secured in the side-frames 5 and 6 are the coacting cutting bars 95 and 96 mounted on the shafts 97 and 98 respectively. The shaft 98 is journalled in the journal boxes 99 sliding in the brackets 100; the springs 101 coiled about the rods 102 secured to the brackets 100 by nuts 103 yieldingly hold the bars 95 and 96 in co-operating relation. The bar 95 carries the circular cutting knives 104 on its periphery (only one knife being shown in Figs. 2 and 4) between the screw-collar 105 and the sliding collar 106 which carries the set-screw 107 adapted to engage in key slot 108 formed in the sleeve 109 secured to the shaft 97. The cutting edge of the knife 104 is adapted to engage with the peripheral

groove 110 formed in the collar 111 adjustably secured to the sleeve 112 by the set-screw 113, the sleeve 112 being fastened to the shaft 98. Any other means for suitably 5 fastening the several sets of knives on the cutting bars 95 and 96 to secure transverse adjustment to properly slit the folded sheets longitudinally may be employed, the means shown being a convenient and practicable 10 form.

The delivery rollers 114 and 115 which take the slitted folded sheets or signatures are mounted on the shafts 116 and 117 respectively, and are suitably disposed below 15 the cutting bars 95 and 96 as shown in Figs. 1 and 2. The shaft 116 is journaled in the brackets 118 secured to the side frames 5 and 6, while the shaft 117 is journaled in the boxes 119 slidably secured in the brackets 118 with the springs 120 coiled about the rods 121 forcing the boxes 119 to the left in Figs. 1 and 2 to yieldingly hold the delivery rollers 114 and 115 in cooperating position.

25 The folding rollers 50 and 51, the cutting bars 95 and 96 and the delivery rollers 114 and 115 are all rotated in unison and at substantially the same peripheral speeds by any suitable mechanism. In the embodiment shown the large gear-wheel 25 on the cam-shaft 26 meshes with the idler gear 121 which engages the drive gear 122. The gear 122 engages with the pinion 123 mounted on the end of the shaft 52 which also 30 carries the gear 124 in mesh with the gear 125 on the shaft 53 to rotate the folding rollers 50 and 51. The drive gear 122 also engages the pinion 126 on the outer end of the shaft 116 which also carries the gear 127 in 35 mesh with the gear 128 on the shaft 117 to rotate the delivery rollers 114 and 115 in unison.

40 Referring to Figs. 1 and 4, I have embodied means whereby the cutting bars 95 and 96 are not only rotated in unison with the folding and delivery rollers, but also 45 may be disconnected therefrom so that each of the cutting bars 95 and 96 may be independently rotatable. This is of advantage 50 so that the cutting edges of the knives 104 may be readily examined and adjusted. In the present embodiment the gear 127 on the shaft 116 meshes with the idler gear 129 which 55 engages the pinion 130 fast to the shaft 97; the pinion 130 engages with the pinion 131 secured to the shaft 98 whereby the cutting bars 95 and 96 are driven in unison. To disconnect same the idler gear 129 is secured to the shaft 132 fastened to 60 the side-frame 5 on the hub 134 slidable on shaft 132 as shown in Fig. 4. Inside the hub 134 on the shaft 132 is the sliding ring 135 held to the shaft 132 by the set-screw 136 as shown, the gear 129 being meshed 65 with the gear 127 and pinion 130. When it

is desired to have the cutting bars 95 and 96 to rotate independently the operator loosens the set-screw 136 and slides the ring 135 inwardly (or to the left in Fig. 4) which enables the gear 129 also to be moved to the left and out of mesh with the gear 127 and pinion 130. By this means the cutting bars 95 and 96 may be independently rotated to make any necessary repairs, inspection or 70 adjustments for the cutting knives carried by such bars.

75 When it becomes necessary or desirable to inspect or remove the cutting bars 95 and 96 or the cutting knives 104, the operator rotates either handle 45 to rack forwardly the carriage 39 which moves outwardly from the position shown in Fig. 1, until the carriage reaches the position shown in Fig. 2, the pinion 123 readily disengaging itself from the drive gear 122, while the folder blade 49 is elevated as the spring 90 is placed under greater compression. The side-registering device heretofore described is not disturbed in its timed relation with the folder blade 49, since the retraction or forward movement of the carriage 39 slides the bracket 71 along the rod 72 as shown in Fig. 2 without disarranging the operating mechanism to secure the properly timed reciprocation for the side-guide plate 69. When the carriage has 80 reached its Fig. 2 position with the folding and sheet-positioning devices supported on the carriage having been collectively moved from operative position, the cutting bars 95 and 96 are fully exposed and the knives 104 may be examined, adjusted or removed, particularly after the idler gear 129 is loosened and moved inwardly on the shaft 132 to disconnect the pinion 130 from the gear 127. All that is required to reassemble the 85 parts in operative position is for the operator to reverse the rotation of the handle 45 to bring the carriage 39 back to its Fig. 1, or operative, position with the folding and sheet-positioning devices together with their 90 respective actuating mechanisms each restored to normal operative positions without altering in any respect their respective timed 95 relations with each other and with the coacting rotary cutting bars 95 and 96 which longitudinally slit the folded sheets or signatures passed downwardly from the folding rollers 50 and 51.

100 The invention is not to be limited to the particular constructions shown, nor to any particular constructions or actuating mechanism by which it may be carried into effect, as many changes and alterations may be made without departing from the principles 105 of the invention and without sacrificing its chief advantages.

110 I claim as my invention:—

115 1. In a machine of the class described, separate sheet folding and positioning devices, a cooperating sheet-slitting mechanism, and 120

- means for collectively moving said folding and positioning devices from and into operative position with the slitting mechanism.
2. In a machine of the class described, 5 separate sheet folding and positioning devices, a cooperating sheet-slitting mechanism, and a single means for collectively moving said folding and positioning devices from and into operative position with the slitting mechanism. 70
3. In a machine of the class described, separate sheet folding and positioning devices, a cooperating sheet-slitting mechanism, and means for collectively and simultaneously moving said folding and positioning devices from and into operative position with the slitting mechanism. 75
4. In a machine of the class described, 10 separate sheet folding and positioning devices, a cooperating sheet-slitting mechanism, and a single means for collectively and simultaneously moving said folding and positioning devices from and into operative position with the slitting mechanism. 80
5. In a machine of the class described, 15 separate sheet folding and positioning devices, means for separately actuating said devices in suitable timed relation, a cooperating sheet-slitting mechanism, and means for collectively moving said folding and positioning devices from and into operative position with the slitting mechanism without altering the relation of said actuating means. 85
6. In a machine of the class described, 20 separate sheet folding and positioning devices, machine-operated means for separately actuating said devices in suitable timed relation, a cooperating sheet-slitting mechanism, and means for collectively moving said folding and positioning devices from and into operative position with the slitting mechanism without altering the relation of said actuating means. 90
7. In a machine of the class described, 25 separate sheet folding and positioning devices slidably mounted in the machine, a slitting mechanism cooperating therewith carried by the machine, and means for collectively shifting said folding and positioning devices from and into operative position with the slitting mechanism without moving the latter. 95
8. In a machine of the class described, 30 separate sheet folding and positioning devices slidably mounted in the machine, a slitting mechanism comprising coacting rotary cutting-bars cooperating therewith carried by the machine, and means for collectively shifting said folding and positioning devices from and into operative position with said cutting bars without moving the latter. 100
9. In a machine of the class described, 35 separate sheet folding and positioning devices slidably mounted in the machine, 105
- separate means for actuating said devices, a slitting mechanism cooperating therewith carried by the machine, and means for collectively shifting said folding and positioning devices from and into operative position with the slitting mechanism without moving the latter and without altering the relation of either of said actuating means to each other and to the slitting mechanism. 110
10. In a machine of the class described, 40 separate sheet folding and positioning devices, a longitudinally movable carriage supporting said devices, a slitting mechanism cooperating with said devices, and means for shifting said carriage from and toward 115 said slitting mechanism. 120
11. In a machine of the class described, 45 separate sheet folding and positioning devices, a longitudinally movable carriage supporting said devices, a slitting mechanism cooperating with 125 said devices, and means comprising a rack and pinion device for shifting said carriage from and toward said slitting mechanism. 130
12. In a machine of the class described, 50 separate sheet folding and positioning devices, separate means for actuating said devices in suitable timed relation, a longitudinally movable carriage supporting said devices, a slitting mechanism cooperating with 135 said devices, and means for shifting said carriage from and toward said slitting mechanism without altering the relation of either of said actuating means to each other and to said slitting mechanism. 140
13. In a machine of the class described, 55 separate sheet folding and positioning devices, separate means for actuating said devices in suitable timed relation, a longitudinally movable carriage supporting said devices, coacting rotary cutting bars to slit the sheets, and means for shifting said carriage from and toward said slitting mechanism without altering the relation of either of said actuating means to each other and to 145 said cutting bars. 150
14. In a machine of the class described, 60 separate sheet folding and positioning devices, separate means for actuating said devices in suitable timed relation, a carriage 155 longitudinally movable supporting said devices, coacting cutting bars to slit the sheets, means for rotating same, and means comprising a rack and pinion device for shifting said carriage from and toward said slitting mechanism without altering the relation of either of said actuating means to each other and to said slitting mechanism. 160
15. In a machine of the class described, 65 folding rollers, means for feeding sheets thereto, separate sheet-positioning devices with means for actuating same, a reciprocating folder blade coacting with said rollers and sheet-positioning devices, a slitting mechanism comprising rotary cutting bars 165

- to longitudinally divide the sheets when folded, and means for collectively moving said folding rollers, sheet-positioning devices and folder blade from and into operative position with the sheet-feeding means and slitting mechanism without altering their respective timed relations.
16. In a machine of the class described, folding rollers, means for feeding sheets thereto, separate sheet-positioning devices with means for actuating same, a reciprocating folder blade coacting with said rollers and sheet-positioning devices, a slitting mechanism comprising rotary cutting bars to longitudinally divide the sheets when folded, and means for collectively and simultaneously moving said folding rollers, sheet positioning devices and folder blade from and into operative position with the sheet-feeding means and slitting mechanism without altering their respective timed relations.
17. In a machine of the class described, folding rollers, means for feeding sheets thereto, separate sheet-positioning devices with means for actuating same, a reciprocating folder blade coacting with said rollers and sheet-positioning devices, a slitting mechanism comprising rotary cutting bars to longitudinally divide the sheets when folded, and a single means for collectively moving said folding rollers, sheet position- 45 devices and folder blade from and into operative position with the sheet-feeding means and slitting mechanism without altering their respective timed relations.
18. In a machine of the class described, folding rollers, means for feeding sheets thereto, separate sheet-positioning devices with means for actuating same, a reciprocating folder blade coacting with said rollers and sheet-positioning devices, a slitting mechanism comprising rotary cutting bars to longitudinally divide the sheets when folded, and means for collectively and simultaneously moving said folding rollers, sheet positioning devices and folder blade from and into operative position with the sheet-feeding means and slitting mechanism without altering their respective timed relations.
19. In a machine of the class described, sheet folding devices, a cooperating sheet-slitting mechanism, and means for moving said folding devices from and into operative position with the slitting mechanism without altering their coacting timed relation.
20. In a machine of the class described, sheet folding rollers, a reciprocating folder blade coacting with said rollers, a slitting mechanism comprising rotary cutting bars to longitudinally divide the sheets when folded, and means for collectively moving said folding rollers and blade from and into operative position with the cutting bars 55 without altering their timed relation with each other and with said cutting bars.
21. In a machine of the class described, sheet folding rollers, a reciprocating folder blade coacting with said rollers, a slitting mechanism comprising rotary cutting bars to longitudinally divide the sheets when folded, and means for collectively and simultaneously moving said folding rollers and blade from and into operative position 60 with the cutting bars without altering their timed relation with each other and with said cutting bars.
22. In a machine of the class described, sheet folding rollers, a reciprocating folder blade coacting with said rollers, a slitting mechanism comprising rotary cutting bars to longitudinally divide the sheets when folded, and means for collectively and simultaneously moving said folding rollers and blade from and into operative position 65 with the cutting bars without altering their timed relation with each other and with said cutting bars.
23. In a machine of the class described, sheet folding rollers, a reciprocating folder blade coacting with said rollers, a slitting mechanism comprising rotary cutting bars to longitudinally divide the sheets when folded, and means for collectively and simultaneously moving said folding rollers and blade from and into operative position 70 with the cutting bars without altering their timed relation with each other and with said cutting bars.
24. In a machine of the class described, sheet folding rollers, a reciprocating folder blade coacting with said rollers, a slitting mechanism comprising rotary cutting bars to longitudinally divide the sheets when folded, and means for collectively and simultaneously moving said folding rollers and blade from and into operative position 75 with the cutting bars without altering their timed relation with each other and with said cutting bars.

HARRY EHLIG.
